(57) **CLAIM**

The ornamental design for a portion of a display panel with an animated computer icon, substantially as shown and described.

DESCRIPTION

FIG. 1 is a front view of a portion of a display panel, showing a first image of an animated computer icon.

FIG. 2 is a front view of a portion of a display panel, showing a second image of an animated computer icon.

FIG. 3 is a front view of a portion of a display panel, showing a third image of an animated computer icon.

FIG. 4 is a front view of a portion of a display panel, showing a fourth image of an animated computer icon.

FIG. 5 is a front view of a portion of a display panel, showing a fifth image of an animated computer icon.

FIG. 6 is a front view of a portion of a display panel, showing a sixth image of an animated computer icon; and,

FIG. 7 is a front view of a portion of a display panel, showing a seventh image of an animated computer icon.

The appearance of the transitional image sequentially transitions between the images shown in FIGS. 1-7. The process or period in which one image transitions to another image forms no part of the claimed design.

The broken line bordering each figure and illustrating the display panel portion forms no part of the claimed design. The broken lines within each figure illustrate graphical environmental features that form no part of the claimed design.
